UNITED STATES PATENT OFFICE.

DAVID W. PORTER, OF CHARLESTON, WEST VIRGINIA.

PISTON.

1,278,205.

Specification of Letters Patent. Patented Sept. 10, 1918.

Application filed July 18, 1917. Serial No. 181,330.

To all whom it may concern:

Be it known that I, DAVID W. PORTER, a citizen of the United States, residing at Charleston, in the county of Kanawha and 5 State of West Virginia, have invented new and useful Improvements in Pistons, of which the following is a specification.

This invention relates to engine pistons, and comprehends the provision of a novel 10 construction of means whereby the packing rings about the piston can be conveniently adjusted or expanded to compensate for the wear of the rings, thus insuring good compression, and maximum power from the 15 motor.

The nature and advantages of the invention will be better understood from the following detail description when read in connection with the accompanying drawing, 20 the invention residing in the construction, combination and arrangement of parts as claimed.

In the drawing forming part of this specification like numerals of reference indicate 25 similar parts in the several views and wherein:

Figure 1 is a vertical sectional view through the piston constructed in accordance with my invention.

Fig. 2 is a transverse sectional view therethrough.

Fig. 3 is a detail view of one of the adjusting members.

Fig. 4 is a transverse sectional view taken 35 on line 4-4 of Fig. 1.

The piston is indicated generally at A and comprises an enlarged lower portion or base 10 from which rises a centrally disposed stem 11. The base 10 is provided with

40 a socket 12 for the reception of one end of the piston rod (not shown), but which is held associated with the piston through the instrumentality of the pin 13. The upper surface of the base 10 is provided with a

45 plurality of radially disposed slots 14, which receive the widest extremity of the stem 15 of the adjusting members clearly shown in Fig. 3. Each of the adjusting members embody a stem 15 having a tapered edge 16

50 while the opposed edge 17 which is perfectly straight has associated therewith an arcuate shaped blade 17, thus giving to the adjustable member a substantially T-shaped formation in cross section. These adjusting members are supported upon the upper sur-

55 face of the base 10 and are disposed so that

the arcuate shaped blades wholly surround or encircle the stem 11. Manifestly the adjusting members may be of any suitable dimensions for the purpose intended, while 60 any number of adjusting members may be employed, the number depending largely upon the size of each member. With the stems 15 arranged in the slot 14 circumferential movement of the members with respect to the stem 11 is obviated. The members are arranged upon the base 10 of the piston in a manner whereby the edge 16 has its tapered surface extending from the stem 11 at an appropriate point in its length upwardly and outwardly toward the extremity 70 of the stem as clearly shown in Fig. 1. Slipped upon the stem 11 is a cone-shaped element in cross section 18 the latter being fitted in the space between the stem 11 and 75 the tapered edges 16 of the adjusting members. Subsequent to the positioning of the cone-shaped member in this manner, the packing rings 19 are spaced about the adjusting members as shown. The adjusting members 80 are of usual construction and of a resilient nature, but to assist in the expansion of the rings to compensate for the wear thereof, I preferably provide each of the adjusting members with a plurality of recesses 20 in each of which is arranged an expansible coil spring 21 having one extremity bearing against the packing rings.

The stem 11 is provided with a relatively small bore 22 of proper length and arranged 90 longitudinally of the stem, while this small bore communicates with a relatively large bore 23 disposed above the small bore and opening at one end of the stem. An externally threaded sleeve 24 is secured within the small bore 22, with a portion of the sleeve projecting centrally within the large bore 23. The stem is provided with spaced elongated slots 25 which are disposed parallel with the bore 22 and communicate 95 therewith while the sleeve 24 is provided with aligned openings 26 which are also disposed in registration with the slots 25, and with a transverse opening 27 in a threadless bolt 28 which is slidably fitted within the 100 sleeve 24. When the cone-shaped element 18 is fitted upon the stem 11 it is rotated to bring the aligned openings 29 thereof in registration with the slots 25 of the stem, and a key 30 is subsequently passed through the cone-shaped element, the stem 11, sleeve 24 and bolt 28, an arrangement which provides for 105

an adjustment of the cone-shaped member simultaneously with the adjustment of the bolt 28. Manifestly when the bolt 28 is moved farther within the sleeve 24, the cone-shaped element is moved in the same direction and coöperates with the tapered edges 16 of the adjusting members, to force the latter outwardly with a view of expanding the packing rings 19 to compensate for 10 the wear thereof.

While the bolt 28 may be adjusted in various ways, I preferably make use of a nut 31 which is threaded upon that portion of the sleeve 24 positioned within the enlarged bore 23 of the stem. The nut is provided with a reduced exteriorly threaded portion 32 which terminates to provide an inwardly directed annular flange 33, and upon which flange reposes the head 28' of 20 the bolt 28, thus supporting the bolt for sliding adjustment in the sleeve 24, when the nut 31 is rotated as will be readily understood. An interiorly threaded cap 34 is threaded upon the reduced portion 32 of 25 the nut and coöperates with the flange 33 to prevent casual derangement of the bolt 28, or movement thereof independently of the nut 31.

The stem 11 projects an appreciable distance above the adjusting members and uppermost packing ring 19, and this portion of the stem is exteriorly threaded to accommodate the piston head 35 which is provided with a threaded opening as shown. A head 35 is also provided with a plurality of diametrically opposed threaded recesses 36 which receive the shanks of threaded fastening elements 37 which latter are passed through openings in a plate 38 for securing 40 the latter upon the piston head 35 and closing the central opening therein.

In practice, when the packing rings 19 have depreciated in size as the result of wear, thus bringing about a loss of compression in motive power, the head of the engine cylinders can be removed and the plate 38 subsequently separated from the head 35 of the piston, thus allowing access to be had to the nut 31. By turning the nut a slight 45 distance to the right, the cone-shaped element 18 is forced downwardly, through the instrumentality of the bolt 28 which provides a connection between the nut 31 and said cone-shaped element. Obviously, as 50 the cone-shaped element is moved downwardly it operates with the inclined edges 16 of the adjusting members, to force the latter outward with a consequent expansion

of the packing rings to insure good compression, and maximum power from the motor. The plate 38 is then replaced as is also the head of the engine cylinders. The construction is not only simple, but provides a means whereby the packing rings can be conveniently expanded for the purpose intended, in quick order. 60 65

While it is believed that from the foregoing description the nature and advantages of the invention will be readily apparent, I desire to have it understood that what is herein shown and described constitutes the preferred embodiment of the invention to which I do not limit myself, and that such changes may be resorted to when desired as fall within the scope of what is claimed. 70 75

What is claimed is:—

1. A piston of the character described comprising a base formed with an upstanding reduced stem portion, said stem being hollow for a portion of its length, a tubular 80 member disposed within the hollow portion, a plurality of wedge-shaped adjustable members surrounding said stem and supported upon the base, a cone-shaped element interposed between the stem and adjustable members, a bolt slidably fitted within said tubular member and wholly disposed within said stem, a connection between the bolt and the cone-shaped member whereby movement of the latter is controlled by said bolt, a nut 90 adjustably mounted upon the tubular member and constituting a support for said bolt, and a cap associated with the said nut for holding the bolt positioned with respect to the nut for movement therewith. 95

2. A piston of the character described comprising a base, having an upstanding centrally disposed stem portion, a plurality of wedge-shaped members surrounding said stem and mounted upon the base, a cone-shaped element slidably fitted upon the stem and interposed between the latter and said adjustable members, said stem being hollow for a portion of its length, means wholly disposed within the hollow portion of the 105 stem for effecting an adjustment of the cone-shaped element, said stem projecting an appreciable distance above the adjustable members and exteriorly threaded, a piston head threaded upon the projected portion 110 of the stem, and a plate detachably secured to said piston head and closing the upper extremity of the stem.

In testimony whereof I affix my signature.

DAVID W. PORTER.
